SMOKE DETECTION UNIT

Jeffrey E. Hamm, 7432 Eastbourne Circle 84121, and
Robert S. Jenson, 2981 Middleton Way 84117, both
of Salt Lake City, Utah

Filed Feb. 8, 1973, Ser. No. 330,528

Term of patent 14 years

Int. Cl. D29—02

U.S. Cl. D72—1 R

FIG. 2

FIG. 1

FIG. 1 is a front perspective view of a smoke detection unit showing our new design.

FIG. 2 is a side elevational view thereof, the major portion of the side being shaded to represent perforations, partially shown for convenience of illustration. The top, opposing side and bottom are similarly recessed and perforated.

We claim:

The ornamental design for a smoke detection unit, as shown and described.
